UNITED STATES PATENT OFFICE.

HENRY SANDERS, OF UTICA, NEW YORK.

IMPROVEMENT IN CULTIVATOR-TEETH.

Specification forming part of Letters Patent No. 26,297, dated November 29, 1859.

To all whom it may concern:

Be it known that I, HENRY SANDERS, of Utica, Oneida county, State of New York, have invented a new and useful Improvement in the Manner of Constructing Cultivator-Teeth of Sheet Metal and Cast-Iron Combined, of which the following is a full and clear description.

I am aware that cultivator-teeth have been made of sheet metal in different ways. One kind is fastened to the cultivator-frame by a wooden wedge, the tooth being mortised in the frame, and the wedge driven in perpendicular with the tooth between the tooth and the frame. This mode of making teeth requires heavy timber for the frame, and much labor is required to mortise them in. Another mode is to cast a head or boss on the tooth for the purpose of attaching the tooth to the frame; but in consequence of casting the head on the tooth the head chills and becomes hard and brittle and breaks loose from the tooth, thereby rendering it useless.

My improvement is intended to remedy these defects.

It consists of two pieces of metal exclusive of the bolt, the tooth being formed of sheet steel or iron, with flanges on the upper end of it, which goes next to the frame. The other piece is made of cast-iron, with flanges on it corresponding with the flanges on the tooth for the purpose of securing the tooth firmly to the cultivator-frame by means of a bolt passing through it and the frame. In order, also, to add strength to the tooth and to relieve the bolt and chair (or piece made of cast-iron) from the pressure that would come on them otherwise, I form on the front part of the tooth, on the top, a semicircular projection about one inch long for a pin that is cast on the chair to fit into, the two when fitted together making

one pin, as it were, which is let into the frame by a hole being bored for that purpose, to receive it, so that when the tooth is fastened to the frame by the bolt this rim on the chair and projection on the tooth act as a brace against the pressure on the tooth when in use, adding strength and durability to it.

To enable any ordinary mechanic to make and construct my invention, I will now proceed to describe it in detail, reference being had to the accompanying drawings, making part of this specification, in which—

Figure 1 is a perspective view of the tooth. Fig. 2 is a perspective view of the chair; and Fig. 3 is a view of the tooth complete, ready to be attached to the cultivator-frame.

Fig. 1 is a tooth swaged out of sheet metal or iron, a piece being cut out of it on each side to allow the flanges to be turned and the semicircular projection to be left standing. *a a* are the flanges, and *B* the semicircular projection.

Fig. 2 is the chair, made of cast-iron, with pin *E* cast on it, and flanges *C C*. *b* is the hole for the bolt *d* in Fig. 3 to pass through.

Fig. 3 is the tooth ready to be secured to the cultivator-frame.

Having thus described my invention in cultivator-teeth and the manner of constructing them, what I claim as new, and desire to secure by Letters Patent, is—

The flanges *a a* and semicircular projection *B* on the tooth, and the flanges *C C* and pin *E* on the chair, when constructed and arranged in relation to each other in the manner substantially as described, and for the purposes set forth.

HENRY SANDERS.
